UNITED STATES PATENT OFFICE.

STEPHEN G. DAVIS, OF RIDGE FARM, ILLINOIS, ASSIGNOR OF ONE-FOURTH TO JOHN E. MCCOY AND ONE-FOURTH TO MILTON BUSBY, JR., OF RIDGE FARM, ILLINOIS.

CHURN-POWER.

No. 836,100.

Specification of Letters Patent.

Patented Nov. 20, 1906.

Application filed May 13, 1905. Serial No. 260,296.

To all whom it may concern:

Be it known that I, STEPHEN G. DAVIS, a citizen of the United States, residing at Ridge Farm, in the county of Vermilion and State 5 of Illinois, have invented a new and useful Churn-Power, of which the following is a specification.

This invention relates to devices for operating churning and like apparatus, and has for 10 its object to improve the construction and increase the efficiency and utility of devices of this character.

With these and other objects in view, which will appear as the nature of the invention 15 is better understood, the same consists in certain novel features of construction, as hereinafter fully described and claimed.

In the accompanying drawings, forming a part of this specification, and in which corresponding parts are denoted by like designating characters, is illustrated the preferred form of embodiment of the invention capable of carrying the same into practical operation, it being understood that the invention 20 is not necessarily limited thereto, as various changes in the shape, proportions, and general assemblage of the parts may be resorted to without departing from the principle of the invention or sacrificing any of its advantages.

In the drawings thus employed, Figure 1 is a side elevation of the improved construction applied to a churn, with the body of the churn partially in section. Fig. 2 is a front elevation of the improved device detached from the churn-body, seen along arrow 2 of Fig. 1. Fig. 3 is a longitudinal sectional elevation on line 3-3 of Fig. 2. Fig. 4 is a plan view of a portion of the frame, detached, on line 4-4 of Figs. 1 and 2. Fig. 5 is perspective views of portions of the framework detached. Fig. 6 is a detail view, partially in section, illustrating the application of the device to a rotary form of churn.

The improved device comprises a base or bed member 10, having a recess 11 in one side to bear against one side of the churn-body (represented at 12), and provided with a clamp member 13, hinged at one end, as at 14, to 45 the member 10 and bearing upon the opposite side of the churn. Extending, respectively, from the base member 10 and the free end of the clamp member 13 are lugs 15, 16,

the lug 15 having a threaded aperture and the lug 16 having a rod 17 rotatively mounted therethrough and with one end threaded for engaging the threaded aperture and the other end terminating in milled disk 18 for rotating the rod. 55

By this construction a simple and effective locking means is provided between the clamp member and the base member and the latter firmly secured upon the churn-body.

The upper edge of the churn-body 12 is provided with a rib 20, over which channels 65 in the recess 11 and the clamp member 13 fit, to increase the "grip" upon the body and prevent slipping.

The device may be readily adapted to any form or size of churn-body, but for the purpose of illustration is shown applied to a circular body of the usual "barrel" form; but it will be understood that any form or size of the body portion may be employed; but as the form or size of the body is not essential 70 the different forms are not further illustrated. 75

The upper face of the base member 10 is provided with a recess 21, in which a supporting-frame 22 rests and swinging therefrom at one end, as by a hinge 23 and as indicated 80 by arrow A, and secured removably in position at the other end, as by a button 24.

The frame 22 is formed with spaced lateral arms 73, 74, having half-bearings in their outer faces, and mounted for rotation in the 85 half-bearing of the lower arm. 74 is a tubular shaft 25, extending into the churn-body 12 and having dasher-blades 26 at the lower end and with the upper end extended and bearing against the under side of the upper arm 73, 90 as shown in Fig. 3.

Extending through the tubular shaft 25 is an internal shaft 28, engaging the half-bearing in the upper lateral arm 73 and with dasher-blades 30 on its lower end below the dasher-blades 26 of the tubular shaft. The tubular shaft 25 is supported in place by a bearing-cap 32, disposed over the half-bearing of the arm 74, and the internal shaft 28 is likewise supported in place by a bearing-cap 31, 100 disposed over the half-bearing of the arm 73, and the two bearing-caps united by a coupling-bar 33, the latter serving as a handle to operate the supporting-frame, as hereinafter described.

The bearings 31, 32 are preferably hinged

at similar ends, as at 34 35, to the frame 22 and detachably secured at the other ends by bolts, as at 36 37, so that the shafts 25 28, with their attached bevel-gears 27 29, together with the dasher-blades carried thereby, may be easily detached when required.

A bevel-gear 27 is attached to the tubular shaft 25 above the lower arm 74 and bears upon the same, and a bevel-gear 29 is attached to the internal shaft 28 above the upper arm 73 and bears upon the same.

Mounted for rotation horizontally of the frame 22 is a shaft 38, having a gear-pinion 39 on one end and a bevel-gear 40 on the other end, the bevel-gear engaging both the bevel-gears 27 and 29.

By this arrangement it will be obvious that when the shaft 38 is rotated the coaction of the gears 40, 27, and 29 will simultaneously rotate the shafts 25 and 28 and in opposite directions, and thus produce a rapid churning motion of the dasher-blades 26 and 30. Attached to the base-frame 10 is another framework 41, having a shaft 42, mounted therein and carrying a coiled spring 43, coupled by one end to the shaft, as at 44, and to the framework 41 by the other end, as at 45. A gear-wheel 46 is loosely mounted upon the shaft 42 and coupled to the shaft by a winding-ratchet mechanism of the ordinary construction and indicated at 47. A counter-shaft 48 is mounted for rotation in the frame 41 and provided with a gear-pinion 49, engaging the gear-wheel 46, and a gear-wheel 50, engaging the gear-pinion 39 on the drive-shaft 38.

By this arrangement the force of the spring 43 will be utilized to operate the churn-dasher members rapidly in opposite directions, and the motion may be continued indefinitely by winding up the shaft 42 as fast as the spring shows signs of running down.

Mounted for rotation in the frame 22 is a shaft 51, carrying a gear-wheel 52, engaged by another gear-wheel 53, carried by the main drive-shaft 38, and also mounted for rotation upon the frame 22, as by bearings 54 55, is another shaft 56, having a "worm" 57, engaged by the gear 52.

Attached to the upper end of the shaft 56 is a disk 58, having levers 59 60 pivoted therein, as at 61 62, and with balls 63 64 at their outer ends and coupled by links 65 66 at the inner ends to a friction member 67, longitudinally slid able, but held from rotary displacement upon the shaft. Disposed beneath the friction member 67 is another friction member 68, held from turning, as by a pin 69, fast to the frame 22, but adjustable vertically upon the shaft. An adjusting-lever 70 is pivoted at 71 to the frame 22 and bearing by one end beneath the friction member 68 and adjustable, as by a screw 72, at the outer end.

By this means a simply-constructed gover-

nor is provided to control the speed of the shaft 25 and 28, and the force of the governor is easily controlled by the screw 72, as will be obvious.

The bearing-caps 31 32 and connecting-bar 70 33 may swing to one side when desired to remove the dasher-shaft, together with their connected bevel-gears, from the churn-body by merely disconnecting the two bolts 36 37, and the entire motor mechanism may be rotatively moved upon the hinge 23 by disengaging the button 24.

The inner end of the main drive-shaft 38 is extended and threaded, as at 80, to receive the threaded end of a coupling member 81, 8c by which the device may be employed for operating an ordinary rotary churn, as indicated at 75 in Fig. 6, the member 81 having a terminal socket 76 for coupling to the crank-shaft 77 of the churn, as shown.

When the device is employed for operating a rotary churn, the vertical dasher-shafts 25 28, together with the gears 27 29, caps 31 32, and connecting member 33, and the churn-engaging bar 13 and clamp-screw 17 will be 90 detached and the frame 10 secured rigidly to some stationary support, such as a table, (indicated at 78,) as by screws 79.

The device is simple in construction, can be readily applied to any form or size of 95 churn-body, and operates effectually for the purposes described.

Having thus described the invention, what is claimed is—

1. A device of the character described 100 comprising a base provided with means for removably embracing a churn, concentric dasher-shafts provided with independent spaced gears, a frame hinged to the base and embodying separable bearings for the dasher-shafts, means for storing mechanical energy, means to convert the stored energy into rotary motion, means to transmit the rotary motion to rotate the gears and dasher-shafts simultaneously in opposite directions and a 105 centrifugal governor operated by and to regulate the speed of the rotary movement.

2. In mechanism of the character described the combination with a base and means for clamping the same upon a churn-body; of a frame hinged on the base, means for locking the frame immovably to the base, telescoping shafts rotatably mounted within the frame, a separable bearing for each shaft, the movable portions of said bearings being integral and hinged to the fixed portions thereof, a motor fixedly connected to the base and power-transmitting mechanism mounted upon and movable with the frame for rotating the shafts in opposite directions 115 120 125 simultaneously.

3. In mechanism of the character described the combination with a recessed base having a curved face and means for clamping a churn-body upon said face; of a frame 130

hinged to the base and seated within the recess, said frame adapted to extend across the recessed clamping-face of the base, dasher-shafts bearing upon the frame, bearing members hinged to the frame for retaining the two shafts thereon said members being rigidly connected, a motor fixedly secured to the base, and power-transmitting mechanism carried by the hinged frame and normally in operative relation with the motor, said mechanism adapted to rotate the

dasher-shafts simultaneously in opposite directions and to be disconnected from the motor when the frame is swung upon its hinge.

In testimony that I claim the foregoing as my own I have hereto affixed my signature in the presence of two witnesses.

STEPHEN G. DAVIS.
